UNITED STATES PATENT OFFICE.

JOHN LEONARD, OF NEW YORK, N. Y., ASSIGNOR TO SOPHIE WIMPFHEIMER, OF SAME PLACE.

DESIGN FOR FRINGE.

SPECIFICATION forming part of Design No. 14,494, dated December 18, 1883.

Application filed October 25, 1883. Term of patent $\frac{1}{2}$ years.

To all whom it may concern:

Be it known that I, JOHN LEONARD, of the city, county, and State of New York, have invented a new and original Design for Fringe, 5 of which the following is a full, clear, and exact description, reference being had to the accompanying drawing, making part of this specification.

This design relates to a fringe; and it consists of a design for a fringe, composed of an ornamental heading, diagonally intercrossing strands which project in bends above the heading, rosettes at the point of intersection of the strands below the heading, and drops or pendants having ball-shaped terminals.

A in the drawing represents a heading, which is made of any suitable ornamental design. Below the heading are arranged diagonally-intercrossing strands B B, which are extended in upward direction back of the heading A, so as to project by their bent upper ends above the heading at the points B' B'. The intercrossing strands B are grouped in pairs at some

distance below the heading, and have at the points of intersection tufted rosettes C, below 25 which the strands are arranged in drops or pendants D of suitable length, said drops terminating in ball-shaped ends D'. A fringe of very ornamental character is thus obtained.

Having thus described my design, I claim 30 as new and desire to secure by Letters Patent—

The design for a fringe, composed of a heading, A, diagonally-intercrossing strands B B, projecting by bends B' above the heading, and grouped in pairs at some distance below the 35 heading, rosettes C, and drops or pendants D D, having ball-shaped terminals D', substantially as shown and described.

In testimony that I claim the foregoing as my invention I have signed it this 13th day of October, 1883.

JOHN LEONARD.
